UNITED STATES PATENT OFFICE.

JAMES CRAWFORD, OF NEW YORK, N. Y.

NUT OR RIVET HOLDER FOR SHEET METAL.

1,272,919.

Specification of Letters Patent. Patented July 16, 1918.

Application filed March 27, 1918. Serial No. 224,974.

To all whom it may concern:

Be it known that I, JAMES CRAWFORD, a citizen of the United States, and a resident of the city of New York, Corona, borough 5 of Queens, in the county of Queens and State of New York, have invented a new and Improved Nut or Rivet Holder for Sheet Metal, of which the following is a full, clear, and exact description.

10 This invention relates to sheet metal constructions and has particular reference to means for connecting one sheet to another adapting the same for disconnection if desired.

15 More definitely stated the primary object of the invention is to provide a means whereby a man working alone is enabled to rigidly secure two sheets together, the operation being performed from one side of 20 the assemblage and without necessitating the operator or an assistant acting upon the other side of the assemblage.

In the building of large sheet metal ventilating shafts or the like for example it is 25 frequently demanded that one section be connected to another section along lines or surfaces that are so closely located adjacent to walls or other obstructions as to make it impossible for the operators to go or reach 30 between the sheet metal structure and such obstruction for the purpose of effecting the connection between the sections and therefore it is important that means be provided to effect the connection entirely from within 35 the shaft. I wish it to be understood, however, that this is but one of many adaptations of my improvement.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which

Figure 1 is a fragmentary detail perspective view which may be understood as representing a large sheet metal ventilating shaft having room within it for the operator to work.

Fig. 2 is a vertical sectional detail on the line 2—2 of Fig. 1, but indicating the bolt 55 prior to introduction into the nut.

Fig. 3 is a horizontal sectional view on the line 3—3 of Fig. 1.

Fig. 4 is a detail plan view of a sheet showing the nut holding means in blank or prior 60 to being swaged or pressed out to receive the nut.

Fig. 5 is a similar view but showing the form or position of the nut holding means with the nut in place therein in dotted lines. 65

Fig. 6 is a detail view of a modification in which the screw is held by one of the sheets in place of the nut, the section being in a plane corresponding substantially to that of Fig. 2.

Fig. 7 is a detail view of the blank adapted to hold the screw or other analogous fastening device such as shown in Fig. 6, the figure being otherwise similar in character to Fig. 4.

Fig. 8 is a view showing the next step from the blank of Fig. 7, but otherwise of the same character as the view of Fig. 5; and

Fig. 9 is a detail view showing a rivet as 80 the fastening member held or carried by the slotted sheet.

Assuming that 10 and 11 are adjacent sections of a sheet metal flue or shaft to be rigidly connected at their overlapping ends 85 and having sufficient capacity for the workman to be located therein, my invention is practised in the following manner, or its equivalent: When designing or building the several sections in the shop or elsewhere one 90 of the sections, being indicated as the outer section 10, is punched or stamped in such a manner as to constitute a holding means for a nut 12 on the side remote from the other section or sheet as indicated in the 95 first five figures. The sheet is slotted at 13 with short parallel slits spaced from each other at a distance substantially equal to the width of the nut. The metal on the opposite sides of these short slits is subsequently bent or swaged out as indicated at 14 forming lugs which serve to positively hold the nut from slipping in the direction of either of these lugs. A pair of longer slits 15 likewise parallel to each other also are 100 formed between the slits 13 leaving between 105

the several slits 15 and slits 13 a pair of straps 16. The length of the slits 15 is approximately equal to or a trifle greater than the width of the nut. The metal between the 5 slits 15 is again slitted at 17 preferably with a cut oblique to the center line joining the slits 13 thereby forming two tongues 18, each having a diagonal end. The next step in the formation of this holder is to bend or 10 swage out the tongues around bending lines 19 thus providing a pocket for the nut where it will be held between the tongues in one direction and between the lugs 14 in the other direction. The free ends 20 of the 15 tongues are then bent down upon the nut positively locking the nut in place. The form of the tongues obviously may be varied according to the thickness of the nut or other conditions, but by beveling the same 20 as indicated I provide a maximum grip upon the outer surface of the nut and yet leave the hole 12' in the nut unobstructed for the introduction of the screw or bolt 21. The straps 16 remain flat or in their 25 natural form and serve to positively support the inner face of the nut and yet provide a clear space through which the screw or bolt may pass. It will be understood that this work of forming the nut holder and 30 fastening the nut therein will be performed in the shop under ordinary practice.

The co-operating sheet or section 11 will be punched with an ordinary hole 22 to register with the nut hole 12' when the sheets are 35 assembled so all the operator has to do in completing the connection or fastening of the sheets or sections is to locate the registering holes and introduce the nut or screw 21 which obviously may be inserted with a 40 screw driver or other analogous tool and from the side of the joint or assemblage opposite the nut, the nut being positively held in place and from rotation by the lugs 14 and tongues 18.

45 It will be understood that the particular character of the fastening device may be varied to a considerable extent and similarly the specific character of the holding means is subject to considerable modification without departing from the broad spirit of my 50 invention. In Figs. 6, 7 and 8, for example, I show a sheet 10' slitted at 15' which in connection with the oblique slit 17 will form two tongues 18'. When the tongues are bent 55 outward around bending lines 19 there is provided an open slot 23 through which the shank of a fastening screw, rivet or the like may pass, while the head thereof will be locked permanently in place by the bending 60 down of the free ends of the tongues 18'. The opposite sheet 11 will simply be provided with a hole to register with and receive the point of the screw or rivet after which the operator stationed only on one

side of the joint or construction may apply 65 the nut 12, or its equivalent. Thus it will be seen that if one or more of the walls of the sheet metal construction be so located with respect to building walls or other obstruction as to make access to one side of the 70 sheet construction inaccessible the fastening may be readily effected by the operator from the other side. Also in many instances it is required to fasten together end to end a series of sections of sheet metal pipes or the 75 like of such length or small diameter as to make it impossible to reach therein for the purpose of effecting the fastening. Therefore, under such conditions the inner section will be provided with that part of the fastener 80 that may be regarded as the fixture such as the nut 12 in Fig. 3 or the screw 21 in Fig. 6, and the remaining part of the fastener will be put thereon from the outside.

The fastening member is shown in Fig. 9 85 in the form of a rivet 21' whose head is held by the tongues 18', the shank of the fastener passing through the slot 23 so that the end of the rivet may pass through the hole provided for this purpose in the companion 90 sheet 11. This adaptation of the invention is especially useful for connecting the lengths of small pipes.

I claim:

1. The herein described sheet metal joint, 95 one sheet being provided with two parallel slits and a slit extending from one slit to the other of the parallel slits, thus forming two free ended tongues which when bent outward from the plane of the sheet form an 100 open slot for the passage of the shank of a fastener, a two part fastener, one part of which is adapted to be gripped within and between said tongues while the other part of the fastener may be attached thereto solely 105 from the other side of the other sheet remote from the tongues.

2. The combination with a pair of sheets to be connected, one sheet having a pair of slits parallel to each other, the metal on the 110 opposite sides of the slits being bent outward forming lugs and being provided also with a pair of free ended tongues formed between said slits, the tongues being spaced from each other substantially equal to the distance 115 between said lugs and forming an open slot, a two part fastener, one part of which is located between said lugs and between the tongues and locked rigidly from movement in any direction with respect to the sheet by 120 the tongues, and the other sheet being provided with a hole registering with said slot whereby the other member of the fastener may be passed through the hole and slot and into the locked part of the fastener.

3. The combination of a sheet provided with a pair of slits and a transverse slit extending from one of the aforesaid slits to the

other in a direction oblique to either of the first mentioned slits, the slitted metal when bent outward thus forming two free ended tongues, the end of each tongue being diagonal to the main part of the tongue, the slitting and the outward bending forming an open slot in the sheet for the passage of

the shank of a fastening member and the tongue ends being sufficiently spaced from each other for the same purpose, and a fastening device coöperating with said slitted sheet.

10

JAMES CRAWFORD.
